UNITED STATES PATENT OFFICE.

LESLIE S. HACKNEY, OF ST. PAUL, MINNESOTA.

AUTOMOBILE HOIST AND TURN-TABLE.

1,003,735.

Specification of Letters Patent. Patented Sept. 19, 1911.

Application filed April 17, 1911. Serial No. 490,641.

To all whom it may concern:

Be it known that I, LESLIE S. HACKNEY, a citizen of the United States, residing at St. Paul, in the county of Ramsey and State of Minnesota, have invented a new and useful 5 Automobile Hoist and Turn-Table, of which the following is a specification.

An object of the invention is to provide means whereby auto-cars and other vehicles 10 may be readily and easily handled for inspection, for repair, and for other purposes, and whereby the work of repairing is made easier and less expensive than heretofore, and the repair-pits now common may be dispensed with.

The invention may be embodied in various forms and materials, and includes the apparatus, combinations and parts more fully set forth in the subjoined detailed 20 description.

One purpose of this invention is to make the inspection of the mechanism of an automobile so convenient and easy that such inspection may be frequently made by the 25 owner or chauffeur, for the purpose of discovering and tightening loose bolts, for cleaning and oiling the machinery, and for the discovery and replacement or repair of any weak or broken parts, thus to avoid 30 danger from accidents.

The invention consists in a hoist having an open base on which the machine to be inspected or repaired may be raised so that the inspector or repairer can easily get at 35 the bottom of the machine, and hoisting devices are arranged to separately raise and lower the four corners independently, thus to allow the machine to be tilted in any direction desired, and to be brought into any 40 position required.

The accompanying drawings illustrate the invention in the form at present deemed most desirable.

Figure 1 is a broken view partly in section, showing the hoist and turn-table with an auto-car thereon. Dotted lines indicate 45 a position to which the car may be brought to bring the mechanism, not shown, of the car into position for convenient access by the repairer. The posts or towers and one 50 side of the base are broken to contract the view. Fig. 2 is a view of the hoist with the car turned halfway over to bring its axles

into upright position. The base is broken to contract the view. Fig. 3 is a broken 55 side elevation of the hoist with a car thereon. Fig. 4 is a broken elevation of the apparatus with a car elevated thereby. Fig. 5 is an enlarged fragmental detail to illustrate the means for shifting the car sidewise 60 preparatory to tilting the car. The view is shown in section on line indicated by α^5 , Fig. 3. Dotted lines indicate the tilting position. Fig. 6 is a fragmental elevation from the right of Fig. 5, showing the hoisting-hook and portions of the chain and upright track. Fig. 7 is a view of the parts that go to make up the adjustable joint shown in Fig. 3, for connecting the upper 65 ends of the towers or posts at each side of the hoist. Fig. 8 is a section of said joint on line α^8 , Figs. 3, 7 and 9. Fig. 9 is a plan of the apparatus broken to contract the view and sectioned to show various features of construction; the hoisting gearing being 70 shown as when applied at only two of the posts. Fig. 10 is an enlarged fragmental view to illustrate more clearly one of the carriage-bars. Fig. 11 is a sectional detail of a carriage-bar on line α^{11} , Fig. 10. Fig. 12 is a fragmental section on line indicated at α^{12} , Figs. 9 and 10.

The apparatus is provided with casters 1 that rest on a smooth floor 2. Said casters may be of any suitable character, and any 85 desired number of wheels may be employed. In the drawings a pair of casters is shown supporting each of two sills 3 at the opposite ends of the apparatus. Upon each of the sills 3 are mounted two posts or towers 40 which may be of any construction that 90 will serve the purpose; there being four towers in all.

The sills are connected together by extensible joists 5 that hold the sills in fixed 95 and rigid relation to each other. Each of said joists may consist of members 6 and 7 fastened respectively to the front and rear sills, a slotted channel-bar 8 fastened by bolts 9 to one of the members 6, and a bolt 100 10 passed through the other member 7, and through slots 11 in the flanges 12 of the channel bar 8 and secured by a nut 13.

The towers are arranged in pairs, a pair 105 being on each side of the hoist, and the towers of each pair are connected with each

other by adjustable side-stays which may consist of rods 14, 15, 16, 17, held by a clamp 18 formed of three plates 19, 20 and 21; the outer plates 19, 20, being provided 5 on their inner faces with two grooves 22, 23, and the inner plate being ungrooved on both faces. The three plates are held together by a bolt 24 that extends through one grooved plate and the middle plate, and is 10 screwed into the other grooved plate.

10 The depth of each groove is less than the diameter of a stay-rod, and the rods are seated therein and gripped between the plates when the bolt 24 is screwed home.

15 By loosening the bolts 10 and 24 the sills 3 and the posts thereon may be adjusted toward and from each other, thus to increase and decrease the length of the hoist so as to accommodate cars of different lengths.

20 Each sill is provided on the top with a channel-rail 25 made of angle-irons to support and guide the rollers 26 that are mounted on the ends of the carriage bars 27, 28 which support the front and rear axles of any

25 vehicle that is to be handled. Said carriage-bars 27 and 28 are of like construction, and each is provided on its upper face with two wheel-seats 29, 30 by which the wheels 31 and the axles 32, 33 of the machine may be supported when the wheels are in their seats. Said wheel-seats 30 may be provided with grooves 34 to keep the wheels from sliding 30 from the seats. The wheel-seats 29, 30 of each carriage-bar are fixed to a top-plate 35,

35 and each top-plate is slidable endwise on and adjustably fixed to its carriage-bar by means of the headed studs 36 extending through slots 37 in the carriage-bar, and is also fastened by a clamp-bolt 38 that is fixed 40 to the carriage-bar body and extends through a slot 39 in the plate 35, so that by loosening the nut of the bolt 38 the plate 35 may be slid toward one or the other end of the carriage-bar, thus to shift the 45 vehicle toward one or the other side of the hoist as may be desired.

At the end of each carriage-bar there is provided means in the form of clevises 40 into which attaching means as hooks 41 may 50 be hooked for the purpose of lifting the ends of the carriage-bars from the sills and also relatively to each other. That is to say, the ends may be raised equally or unequally to keep the vehicle level or to tilt it.

55 The hooks 41 are carried by sprocket-chains 42 respectively, said chains being provided with cross-bars 43 and the hooks being hook-shape at both ends; one of said ends 44 being adapted to engage any of the bars 43 60 of the chains so that the hooks may be connected to the chains at any portion thereof.

The chains 42 shown are endless sprocket-chains carried by pulleys 45 at the tops of the posts 4 and driven by sprocket-wheels 46 65 at the bottom of said posts. The driving

sprocket-wheels 46 are controlled by suitable gearing 47 which will be more fully described hereinafter, said gearing being operated in one direction by any suitable means as by the crank 48, and releasably held from 70 reverse rotation by any suitable means as a brake or ratchet. In the drawings, for this purpose a pawl 49 engages a ratchet-wheel 50. Each post, its chains, sprocket-wheels and the gearing to drive the lower sprocket- 75 wheel, constitutes a hoisting mechanism or device capable of raising and lowering the end of the carriage-bar to which its chain may be connected.

When all of the hooks 41 are caught in the 80 clevises 40 and are also caught upon the cross-bars 43 of the sprocket-chains, the hoisting devices may be made to lift all ends of the carriage-bars 27 and 28 equally and thereby bodily lift any vehicle that may be 85 on said bars, thus carrying the vehicle up to any desired height and enabling the attendant to go beneath the vehicle to give attention to the mechanism thereof.

In order to hold the vehicle firmly on the 90 carriage-bars and also to support the same on said bars with the wheels 31 free from the wheel-seats 29, jacks composed of swivel-headed screws 51 screwed into bases 52 that may in some instances be fastened by bolts 95 53 to the sliding-plate 35, are provided with clips 54 by which the jacks may be fixed to the axles 32 and 33. There are four such jacks, two being provided for each axle-tree. The bases and tops of said jacks may be 100 provided with ears 55, 56, and into these ears are hooked stay-rods 57, 58 that are adjustably connected with each other by adjustable joints 59 corresponding to those previously described as being composed of 105 plates 19, 20 and 21, and bolt 24, and specifically shown in Figs. 7 and 8. By loosening the bolts 60 of said joints 59, the rods may be slid through the joints, thus allowing the jacks to be adjusted toward and from each 110 other when the bolts 53 for securing said jacks to the plate 35 have been unscrewed to allow the grooved plates to turn relatively; it being understood that where such adjustment of the jacks on the plate is required 115 extra holes 61 for the bolts 53 may be provided.

Adjustable stays of the character just described are applied not only between the jacks of each carriage, but also between the 120 jacks of each side of the apparatus, so that when the apparatus is lengthened or shortened the sliding joints 59' of the longitudinal stays formed by the rods 57', 58' may be adjusted as required.

A crank and hoisting gearing may be provided for each of the driving sprocket-wheels at each of the posts, or one for the driving sprocket-wheels at one of the posts on each side. In Fig. 9 of the drawings the 130

hoist-mechanisms of one side are connected by a shaft 62 and the hoist-mechanisms of the other side are connected by a shaft 63; and couplings 62' and 63' respectively are 5 provided for said rods adjacent the posts so that the mechanisms may be disconnected in case it is desired to operate the hoisting devices independently of each other.

When it is desired to tilt the automobile 10 the hoisting-hooks on one side of the apparatus will be unhooked from their clevises and also from their chains if desired; and a flexible connection 64 which is provided at its ends with hooks 65 and 66 will be applied to 15 connect the clevises thus released with the outside limbs of the chains 42, the flexible connections 64 being passed down underneath the sprocket-wheels and chains on that side of the apparatus to connect with their clevises. Then as the attendant turns the 20 crank 48 on one side of the machine to draw the hooks 41 on that side of the machine upward,—said hooks being hooked over the bars on the inner limbs of the ends of the 25 sprocket-chains,—another attendant may hold back on the crank 48 on the other side of the apparatus, thus easing the lower end of the carriage-bar toward the posts up which the carriage-bars are being drawn. 30 In this way the automobile may be brought into position with the axles upright as shown in Fig. 2.

In the form shown in Fig. 2 the jacks are not provided with the ears and the 35 brace-rods shown in Fig. 1, but brace-rods 67 are applied between the top plate 35 of the carriage-bar and the axle 32 of the automobile, and said axle is drawn toward the carriage-bar by turnbuckles 68 that are 40 jointed to the carriage and to the brace-rods 69, which brace-rods have slotted feet 70 through which bolts 71 having spanner-nuts 72 thereon are passed, so that said feet 45 may be slipped along the top plate in case adjustment therealong is required.

When it is desired to lower the car to horizontal position from the position shown in Fig. 2, the appropriate housing-mechanism will be operated to draw the flexible 50 connection 64 toward the posts toward which the lower ends of the carriage-bars must be moved in order to lower the vehicle to horizontal position. At the same time another attendant will hold back on the hoisting-mechanism at the side from which the vehicle is being lowered, and in this manner 55 the vehicle will be again brought to horizontal position. Then if it is desired to elevate the vehicle, the flexible connections 60 64 will be unhooked from the carriage-bars, and the clevises thus released will be again connected by the hoisting-hooks 41 with the inner limbs of the sprocket-chains. Thereupon, by simultaneously operating the hoisting-devices the machine may be lifted bodily 65

and horizontally to any position, and may also be tilted by operating the hoisting-devices so as to raise and lower the various ends of the carriage-bars relatively to each other; thus to allow one end of one bar to 70 descend while another end of the bars is ascending.

In case it is found after the automobile is fixed to the top or sliding plate 35 that it is desirable to shift the automobile toward 75 one or the other of the posts, the flexible connections 64 may be hooked into the eyes 73 at the ends of the sliding plates 35, and the cranks may be operated upon that side, thus to cause the flexible connections to pull 80 the sliding plates toward that side of the hoist.

The gearing 47 may be of any requisite character, and in the views is shown as consisting of a pinion 74 meshing with a 85 spur-wheel 75 to which a pinion 76 is fixed, the same meshing with a spur-wheel 77 fixed on the stub-shaft 78 of the driving sprocket-wheel. Set-screws 79 enable the operator to disconnect the spur-wheels 77 from the 90 stub-shaft when it is desired to operate the driving sprocket-wheel at that post from the crank at another post operating through the shaft 62 or 63.

The apparatus may be installed in a 95 garage or machine-shop, or in any other place where the vehicle to be raised and lowered, or to be tilted for inspection or repair, or for dumping loads therefrom, or for any other purpose,—is to be handled; and 100 may be trundled about the floor on the casters 1 which are swiveled so that the apparatus may be turned to any position that may be desired in order to get the best light 105 on the work. The open base frame composed of the sills and joists will interfere but slightly with the movements of the person who desires to inspect or to operate on the mechanism at the under-side of the machine, and the operator may stand on the 110 floor and do the work upon the parts of the machine thus made easily accessible.

It is understood that I have thus produced a hoist for vehicles in which supports for the vehicles are provided, the same being 115 adapted to move evenly to raise the vehicle while the vehicle is level, and also unevenly to tilt the vehicle; and that by raising and lowering the support at one end of the vehicle meanwhile allowing the other end of the vehicle to rest freely on its wheels, the vehicle may be upended, and it is to be understood that while I have shown sprocket wheels and chains, hooks for connecting the inner sides of the chains with the object 120 of the vehicle to be raised and lowered, and flexible connections adapted to pass under the lower sprocket wheels and to be detachably connected with such object to move the same 125 toward or ease the same from the sprocket 130

wheel under which the connection is passed, that any known substitutes for sprocket chains and other devices thus shown may be employed without departing from the spirit of this invention.

It is understood that the chains may be operated to lift the wheels clear from their seats when this is required for the purpose of taking off the wheels, and that the vehicle thus upheld by the jacks alone may be handled as before described.

Vertical tracks 80, 81 are provided on the inner side of each post for the rollers 26 so that when the carriage-bars are drawn into tilting position said rollers will allow the ends of the bars to move up freely. Said tracks are formed of angle-irons to constitute guides to prevent the rollers from moving laterally off the track.

Props 82 may be inserted under the carriage bars, and such bars lowered to rest thereon when an automobile is elevated as shown in Fig. 4, thus to more or less take off the strain from the chains and to insure great safety.

The bars 27 and 28 and the connections between the same and the vehicle form an open frame to support the vehicle and allow free access to the underside of it, and other forms of frame than that shown may be employed for the same purpose without avoiding the invention.

I claim:

1. Four seats for vehicle wheels, rigid means to connect the seats together in pairs, rollers at the ends of said rigid means, upright and horizontal tracks upon which said rollers are adapted to roll and means to raise and lower an end of said rigid connecting means while the rollers are in contact with the tracks.

2. A hoist comprising a movable base, bars on said base, rollers at and extending operably beyond the ends of the bars, upright and horizontal tracks for said rollers, hoisting devices for detachable connection with the bars, and means detachably connecting the hoisting devices with the ends of the bars respectively, for the purpose of drawing the bars along the tracks with the rollers in engagement with said tracks.

3. A hoist comprising a bar, a plate adapted to slide on said bar, means on said plate to support one end of a vehicle, vertical endless chains adjacent the ends of said bar,

means to operate the chains, and means to alternatively connect the ends of said bars with the opposite sides of said chains.

4. The combination of two posts, sprocket wheels at the tops of said posts, sprocket wheels at the bottoms of said posts, endless chains around the sprocket wheels of the respective posts, a bar between the posts, means to operate the lower sprocket wheels respectively, means for detachably connecting an end of the bar with the inner side of the chain adjacent thereto, and a flexible connection adapted to extend under the lower sprocket wheel and to detachably connect an end of the bar with the outer side of the chain adjacent thereto.

5. A hoist comprising four endless chains, four posts, sprocket-wheels on said posts to support the chains, sprocket-wheels underneath the first-mentioned sprocket-wheels to drive the chains, gearing to operate the chains respectively, a bar between two of said posts, means for detachably connecting the ends of one bar with the inner sides of the chains adjacent thereto, a flexible connection adapted to extend under a lower sprocket-wheel and to alternatively connect the ends of said bar with the outer sides of said chains, means to detachably connect the ends of the other bar with the inner sides of the other two chains and to connect the ends of said bar alternatively with the outer sides of the last-named chains.

6. A vehicle hoist comprising a base, bars on said base, rollers at the ends of the bars to rest upon the base, hoisting devices, detachable means for connecting the hoisting devices with the ends of the bars respectively, and means for easing the bars toward the hoisting devices on one side in cases where such devices are operated to tilt the vehicle.

7. A hoist comprising two bars, means to connect said bars to a vehicle, vertical endless chains adjacent the ends of said bars, means to operate the chains, and means to alternatively connect the ends of said bars with the opposite sides of said chains.

In testimony whereof, I have hereunto set my hand at Los Angeles, California, this 10th day of April, 1909.

LESLIE S. HACKNEY.

In presence of—

JAMES R. TOWNSEND,
M. BEULAH TOWNSEND.
